BLASTING CARTRIDGE

Frank H. Armstrong, Michigan City, Ind., assignor, by mesne assignments, to Safety Mining Company, Chicago, Ill., a corporation of Illinois

Application December 7, 1934, Serial No. 756,512

18 Claims. (Cl. 102—6)

This invention relates to blasting cartridges, and more particularly to improvements in a blasting cartridge of the type known as an "air shell" wherein a high pressure gas is employed as a blasting medium.

An object of this invention is to provide an improved blasting cartridge of the type known as an "air shell" designed for use in the "air shooting" of coal or similar materials. Another object is to provide an improved cartridge having its connection with a high pressure gas source and its discharge means for the blasting charge arranged at the same end of the pressure container. A further object is to provide in a blasting cartridge of the above character an improved combined terminal cap and discharge head formed in a single element and arranged at the outer end of the pressure container. Yet another object is to provide an improved cartridge having pressure discharge means controlled by a differential valve mechanism, the discharge control valve arranged at the outer end of the pressure container and the control chamber containing a valve control plunger arranged at the inner end of the pressure container. These and other objects will, however, subsequently more fully appear.

In the accompanying drawing there is shown for purposes of illustration one form which the invention may assume in practice.

30 In this drawing.—

The figure is a view in longitudinal section of the illustrative embodiment of the improved blasting cartridge.

In this illustrative construction there is shown 35 a blasting cartridge of the type known as an "air shell" wherein a high pressure gas such as air compressed under high pressure, is employed as a blasting medium and this cartridge comprises a pressure container 1 of elongated cylindrical 40 form having a pressure chamber 2. Threadedly secured at 3 within the inner end of the container is a control cap 4, while threaded within the outer end of the container at 5 is a combined terminal cap and discharge head 6. This 45 element 6 has an axial discharge orifice 7 terminating in radial discharge ports 8. A conical control valve 9 seats on the wall surrounding the inner end of the discharge orifice 7 to close the outer end of the pressure chamber 2, and this 50 valve has an axial guide extension 10 which cooperates with a bore formed in the element 6 to center and guide the valve 9 with respect to its seat. Formed in the control cap 4 is an axial control chamber 11 containing a plunger 12 connected by a valve rod 13 to the valve 9, this valve

rod extending axially within the pressure chamber 2 and threadedly secured to the valve 9 at 14. Secured to the outer face of the plunger body is a cup leather 15 held in position by a keeper 16 threaded on the valve rod, and this cup leather serves to prevent leakage of high pressure gas from the outer end of the control chamber past the plunger to the inner end of the control chamber at the inner side of the plunger. Held in position within the inner end of the container by the cap 4 is a metallic plate 17 through which the valve rod extends and which carries a hat leather 18 which seals the valve rod and functions as a check valve to prevent leakage from the control chamber past the valve rod to the pressure chamber 2 while permitting flow of high pressure gas from the pressure chamber past the valve rod to the outer end of the control chamber at the outer side of the plunger. The valve rod 13 is preferably made in two parts secured together by a connecting member 19 having arranged therein a valve chamber for receiving a ball check valve 20. The valve rod is axially bored at 21 and communicates at its inner end through a passage 22 in the plunger 12 with the control chamber 11 at the inner side of the plunger, and through a passage 23 controlled by the check valve 20 with the pressure chamber 2. High pressure gas from any suitable source is conducted, under remote control, through tubing 24 connected by a nipple 25 to a plug 26 secured within the element 6. The plug 26 is provided with an axial bore 27 which conducts fluid to a bore 28 formed in the valve guide extension 10 and valve 9 and communicating with the bore 21 of the valve rod. The element 6 contains a packing at 29 to prevent leakage of fluid past the guide extension 10 to the discharge orifice 7.

To perform the blasting operation, the cartridge is placed in a drill hole in the material to be broken and is suitably held therein as by tamping and the tubing 24 extended from the cartridge to a suitable source of high pressure gas. When the cartridge is so positioned, high pressure gas, controlled from a remote point, is admitted through the tubing 24, through the bore 28 in the valve guide extension and valve, through the valve rod bore 21, and past the check valve 20, through the passage 23 to the pressure chamber 2. At the same time fluid flows through the valve rod bore, through passage 22 to the control chamber 11 at the inner side of the plunger 12, the pressure acting on the inner pressure area of this plunger to hold the valve 9 firmly against its seat. When a predetermined blasting

pressure is attained within the pressure chamber 2 the supply of high pressure gas to the tubing 24 is cut off and the pressure in this tubing suitably vented to atmosphere or otherwise reduced. 5 The pressure in the control chamber 11 at the outer side of the plunger 12, acting on the outer pressure area of the plunger, moves the latter inwardly when the pressure at the inner side of the plunger has been reduced, thereby moving 10 the control valve 9 into its open position, and as a result the blasting charge is suddenly discharged from the chamber 2 through the discharge orifice 7 and radial discharge ports 8 to act on the material to be broken. Obviously the 15 valve 20 may be suitably loaded to insure pressure within the extreme inner end of chamber 11 closing valve 9 before pressure flows into chamber 2; though of course the operator will preferably cause the valve 9 to be closed before beginning to 20 admit pressure through the line 24. These and other uses and advantages of the improved blasting cartridge will be clearly apparent to those skilled in the art.

While I have in this application specifically described one form which my invention may assume in practice, it will be understood that this form of the same is shown for purposes of illustration, and that the invention may be modified and embodied in various other forms without departing from its spirit or the scope of the appended 30 claims.

What I claim as new and desire to secure by Letters Patent is:

1. In a blasting cartridge, a container having 35 an orifice at its outer end through which fluid may be discharged, means at the outer end of the container for charging it with a highly compressed fluid, and a fluid pressure controlled valve at the outer end of said container for controlling said discharge orifice and moving inwardly to open the same.

2. In a blasting cartridge, a container adapted to be charged with a highly compressed fluid and having an orifice at its outer end through which 45 such fluid may be discharged, a fluid pressure controlled valve at the outer end of said container for controlling said discharge orifice, control means arranged at the inner end of the container for controlling said valve, and means for both conducting compressed air to the container 50 and operatively connecting the valve and control means.

3. In a blasting cartridge, a container having a discharge orifice at its outer end through which 55 fluid may be discharged, means at the outer end of the container for charging it with a highly compressed fluid, and a fluid pressure controlled valve for governing said orifice and positioned at the discharge end of said container adjacent 60 said orifice and moving inwardly to open the same.

4. In a blasting cartridge, a container adapted to be charged with a highly compressed fluid and having at its outer end a combined terminal 65 cap and discharge head through which the container is charged and said fluid may be discharged, a fluid pressure controlled valve for governing said orifice and positioned within said container adjacent said orifice, and control 70 means for said valve arranged at the inner end of said container.

5. In a blasting cartridge, a container having at its outer end an orifice through which fluid 75 may be discharged, means at the outer end of the container for charging it with a highly com-

pressed fluid, and a fluid pressure controlled valve operative in one position to seal said orifice and positioned in the container between said orifice and the inner end of said container.

6. In a blasting cartridge, a container adapted 5 to be charged with a highly compressed fluid having an orifice at its outer end through which such fluid may be discharged, and a fluid pressure controlled valve for governing said orifice, said valve being positioned at the discharge end of said container adjacent said orifice, control means for said valve arranged at the inner end of said container, and means for conducting fluid pressure from the outer end of said container to the inner end thereof to actuate and control said valve control means and to charge said container.

7. In a blasting cartridge, a container having a pressure receiving chamber, a combined discharge head and terminal charging cap secured to the outer end of said container, a control cap 20 secured to the inner end of said container, said discharge head having a discharge orifice, a valve for controlling the discharge of pressure from said chamber through said orifice, and a control plunger reciprocable in a bore in the control cap 25 and connected to said valve.

8. In a blasting cartridge, a container having a pressure receiving chamber, a combined discharge head and terminal cap secured to the outer end of said container, a control cap 30 secured to the inner end of said container, said discharge head having a discharge orifice, a valve for controlling the discharge of pressure from said chamber through said orifice, a control plunger reciprocable in a bore in the control cap 35 and connected to said valve, and means at the outer end of said container for supplying high pressure gas to said pressure chamber and said control chamber.

9. In a blasting cartridge, a container having 40 an orifice at its outer end through which fluid may be discharged, means at the outer end of said container for charging it with a highly compressed fluid, a fluid pressure controlled valve at the outer end of said container for controlling 45 said discharge orifice, and control means arranged at the inner end of the container and mechanically connected with said valve for controlling the latter.

10. In a blasting cartridge, a container having 50 an orifice at its outer end through which fluid may be discharged, means at the outer end of the container for charging it with a highly compressed fluid, a fluid pressure controlled valve at the outer end of said container for controlling 55 said discharge orifice, and control means arranged at the inner end of said container beyond the inner end of said chamber for controlling said valve.

11. In a blasting cartridge, a container having 60 a discharge orifice at its outer end through which fluid may be discharged, means at the outer end of the container for charging it with a highly compressed fluid, a fluid pressure controlled valve for governing said orifice and positioned at the 65 discharge end of said container adjacent said orifice, and control means for said valve including a pressure fluid actuated member at the inner end of said container.

12. In a blasting cartridge, a container providing 70 a chamber adapted to be charged with a highly compressed fluid and having a discharge orifice and a valve for controlling said orifice, controlling means for said valve, and means for supplying fluid to said chamber and valve con- 75

- trolling means including a passage formed in and extending through said valve.
13. In a blasting cartridge, a container providing a chamber adapted to be charged with a highly compressed fluid and having a discharge orifice and a valve for controlling said orifice, and having seat and back portions, controlling means for said valve, and means for supplying fluid to said chamber including a passage formed 5 in said valve for conducting fluid through the latter in the direction from seat to back thereof.
14. In a blasting cartridge, a container providing a chamber adapted to be charged with a highly compressed fluid and having a discharge orifice and a valve for controlling said orifice which is movable into said chamber to open, controlling means for said valve, and means for supplying fluid to said chamber including a passage formed in said valve.
15. In a blasting cartridge, a container providing a chamber adapted to be charged with a highly compressed fluid and having a discharge orifice and a valve for controlling said orifice which is movable into said chamber to open, controlling means for said valve, and means for simultaneously supplying fluid to said chamber and controlling means including a passage formed in said valve.
16. In a blasting cartridge, a container for re-

ceiving a charge of blasting pressure, discharge means at the outer end of said container, pressure controlled control means at the inner end of said container operative, while the container pressure remains constant, to effect opening movement 5 of said discharge means, for governing said discharge means, and means at the outer end of said container for charging the same.

17. In a blasting cartridge, a container for receiving a charge of blasting pressure, discharge 10 means at the outer end of said container, pressure controlled control means at the inner end of said container for governing said discharge means, and means at the outer end of said container for charging the same and delivering 15 pressure to said control means.

18. In a blasting cartridge, a container, a partition adjacent the inner end of the container for dividing it into a blasting charge receiving chamber outwardly of the partition and a control 20 chamber inwardly of the partition, discharge means for the blasting chamber at the outer end of said container, and pressure controlled control means positioned entirely within the control chamber operative when the pressure in 25 the charge receiving chamber is superatmospheric and while said pressure remains uniform to effect opening of said discharge means.
